UNITED STATES PATENT OFFICE.

GLENN D. LANHAM, OF BAY CITY, MICHIGAN.

HEAD AND VALVE CONSTRUCTION FOR INTERNAL-COMBUSTION ENGINES.

Application filed December 7, 1922. Serial No. 605,493.

To all whom it may concern:

Be it known that I, GLENN D. LANHAM, a citizen of the United States of America, and a resident of Bay City, in the county of 5 Bay and State of Michigan, have invented certain new and useful Improvements in Head and Valve Constructions for Internal-Combustion Engines, of which the following is a specification.

10 This invention relates to improvements in valve mechanisms for internal combustion engines and the like.

One object of the invention is to provide a rotating valve structure which will eliminate the numerous parts which make up the intake and exhaust valves, controlling the admission of fuel, and the discharge of exhaust gases in the conventional internal combustion engines at present in general use.

20 Another object is to design a rotary valve having passages therein which alternately register with the intake and exhaust passages.

A further object is to design a water 25 cooled valve and head which will not heat, the passages in which will however act as hot spots for vaporizing the inrushing gases.

A still further object is to design a simple and compact head and valve which will 30 prevent the leakage of oil into the cylinders, which can be easily assembled and removed, and which can also be fitted to any type of internal combustion engine.

With the above and other objects in view, 35 the present invention consists in the combination and arrangement of parts, hereinafter more fully described, illustrated in the accompanying drawings, and particularly pointed out in the appended claims, it being 40 understood that changes may be made in the form, size, proportion and minor details of construction, without departing from the spirit, or sacrificing any of the advantages of the invention.

45 In the drawing:—

Fig. 1 is a fragmentary side view of an internal combustion engine illustrating my improved head in place thereon.

Fig. 2 is a top plan view thereof.

50 Fig. 3 is an enlarged part sectional view of the valve proper.

Fig. 4 is a fragmentary cross sectional view of the head and valve, the section through the valve being taken on the line 55 4-4 of Fig. 3.

Fig. 5 is a fragmentary view of the valve

structure illustrating an elongated fuel opening.

Referring now particularly to the drawing in which I have shown the preferred embodiment of my invention. The numeral 1 indicates the cylinders of a conventional internal combustion engine on which I have shown my improved head 2. This head is split as shown at 3 and is secured in position on the engine by means of the several bolts 4 which can be anchored, or threaded into the walls of the cylinders proper.

A single valve structure is adapted to be rotatably mounted in this head 2 and comprises a hollow cylindrical member 5 having a plurality of fins or ribs 6 formed thereon in spaced relation to prevent the leakage of oil, corresponding grooves being formed in the head proper to accommodate the said ribs or fins and it will be obvious that the valve can be easily and uniformly lubricated. Cored passages 7 are formed in the valve as clearly shown in Fig. 3 of the drawing, each passage being disposed in angular relation so that as the valve is rotating, the walls of said passages will act as impellers to force the water or other liquid therethrough.

An exhaust pipe 8 is secured to the top of the head in the usual manner, and passages 9 are formed in the head so that when the valve is in position as shown in Fig. 4 of the drawing, communication will be established between the cylinder and the exhaust pipe through the passages 7, 9 and 10, continued rotation of the valve will close the exhaust passage and open the intake passage 11, to which the intake manifold 12 is connected, the passage 7 then registers with the passages 11 and 13 and establishes communication with the cylinders for drawing fuel thereinto, the valve should turn about fifteen degrees after the exhaust closes to insure proper opening and the best results. In Fig. 5 I have shown a fragmentary view of the valve with a different shaped passage therein, and I wish it clearly understood that the opening into the passage 7 may be of any configuration desired, so that a short or prolonged part opening may be secured. This passage 7 also serves to vaporize the fuel being fed to the engine, as every other charge passing through the passage will be exhaust gases, consequently the passage will be hot and will thoroughly vaporize the incoming fuel.

One end of the valve proper is of a smaller diameter, and this hub 14 is turned to receive a sprocket (not shown) which can be driven in any desired manner, but I prefer to use a silent chain connected to a sprocket on the crank shaft, the housing being formed as shown at 15 to accommodate the said sprocket and chain.

The head proper is cored as shown, and a pipe 16 establishes communication between the cored portion of the head and the interior of the valve proper, and outlet 17 being provided, and in practice is connected to the radiator in the usual manner.

15 A gasket 18 is of course provided to make a tight joint in the head and the exhaust and intake passages can be formed to present the least resistance to the flow of the gases, these are however structural details 20 which will be adjusted in practice.

From the foregoing description, it will be obvious that I have perfected a very efficient, simple and practical head and valve structure which will eliminate all the usual intake and exhaust valves and other miscellaneous parts, which will be economical to build and easy to assemble and maintain.

What I claim is:—

1. In a device of the class described, a 30 cored detachable head located above the cylinders and having intake and exhaust ports above the center thereof, a hollow cylindri-

cal rotary valve mounted therein, ribs on said valve and grooves in the head adapted to co-operate therewith, angular passages in the valve in spaced relation, said passages being formed to act as impellers to force water or other liquid therethrough, each passage registering with the intake port in one position and registering with the exhaust port in another position, and a connection between the interior of the head and the valve for forcing a cooling agent therethrough.

2. In a device of the class described, a cored detachable split cylinder head located above the cylinders and having intake and exhaust ports above the center thereof, a single hollow cylindrical valve rotatably mounted therein, a hub formed thereon, angular passages formed in the valve in spaced relation and shaped to act as impeller to force water or liquid therethrough and adapted in one position to establish communication between the intake port and the cylinder, and in another position to establish communication between the exhaust port and the cylinder, means for driving said valve, and a connection between the head and the valve to allow a cooling agent to circulate therethrough.

In testimony whereof I affix my signature.

GLENN D. LANHAM.
